(57) **CLAIM**

The ornamental design for a pet helmet with eye shield, as shown and described.

DESCRIPTION

FIG. 1 is a front and left side perspective view of a pet helmet with eye shield showing my design;

FIG. 2 is a rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, left side perspective view of the pet helmet with eye shield of FIG. 1, showing the eye shield in a first raised position;

FIG. 10 is a front, left side perspective view of the pet helmet with eye shield of FIG. 1, showing the eye shield in a second raised position;

FIG. 11 is a front, left side perspective view of the pet helmet with eye shield of FIG. 1, showing the eye shield in a third raised position; and,

FIG. 12 is a front and left side perspective view of the pet helmet with eye shield of FIG. 1 in condition for use.

The broken lines in the drawings depict portions of the pet helmet with eye shield that form no part of the claimed design. The broken lines showing a helmet strap in FIG. 12 depict environmental structure that forms no part of the claimed design. All broken lines form no part of the claim.

1 Claim, 12 Drawing Sheets
